RAILWAY SIGNALING

Filed Dec. 10, 1929

UNITED STATES PATENT OFFICE

CHARLES A. BROOKS, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed December 10, 1929. Serial No. 413,028.

My invention relates to railway signaling, and particularly to single track signaling of the type in which the signals are controlled from a remote point, such, for example, as 5 a despatcher's office. One feature of my invention is the provision of novel and improved means for interlocking the control of two signals governing traffic in opposite directions through a block, so that neither signal 10 can be cleared unless the other signal is at stop.

I will describe one form of signaling apparatus embodying my invention, and will then point out the novel features thereof in 15 claims.

The accompanying drawing is a diagrammatic view showing one form of apparatus embodying my invention.

Referring to the drawing, the reference 20 characters 1 and 1^a designate the track rails of a stretch of railway track along which traffic moves in both directions. These rails are divided by insulated joints 2 to form a block A—B, and the rails of this block are 25 further divided by similar joints to form two track sections A—C and C—B. Each of these track sections is provided with the usual track circuit, comprising a battery 12 connected across the rails at one end of the section 30 and a track relay T connected across the rails at the other end of the section. Traffic moving toward the right through block A—B is governed by a signal E^A, and traffic moving toward the left through this block is 35 governed by a signal E^B.

Located at the point A is a normally open remote controlled relay S^A. The controlling circuits for this relay form no part of my present invention, and it is sufficient to say 40 that the relay may be closed or energized at will by manual operation of a suitable circuit controller at a remote point, such as a despatcher's office. A similar relay S^B is located at the point B.

Also located at point A is a directional re-

lay D^A, having a normal winding 10, a reverse winding 11, and an armature 7 which is moved to a normal or a reverse position according as the normal or reverse winding is energized, and which armature remains in 50 the position to which it was last moved when the relay becomes de-energized. A similar relay D^B is located at point B.

Also located at point A is a normally open signal controlling relay H^A, and a similar 55 relay H^B is located at point B. Each signal is controlled by a front contact 9 of the associated relay H and by a front contact 13 of the associated track relay T, as hereinafter explained.

Each end of the block is provided with a battery designated by the reference character F with a suitable distinguishing exponent.

When the remote controlled relay S^A is open, the normal winding 10 of relay D^A is 65 energized by a circuit which passes from the upper terminal of battery F^A, through back contact 6 of relay S^A, and winding 10 to the middle point of battery F^A. Winding 10 being energized, contact 7 of this relay is 70 held in its normal position. The normal winding 10 of relay D^B is energized by a similar circuit when the associated remote controlled relay S^B is open.

I will now assume that, with the parts in 75 the positions in which they are shown in the drawing, the despatcher desires to clear signal E^A in order to permit a train moving toward the right to pass through block A—B. To do this, he will cause relay S^A to become 80 energized or closed, thereby opening the circuit for the normal winding 10 of relay D^A at contact 6. A circuit for the reverse winding 11 of relay D^A will then be closed, which circuit passes from the lower terminal of battery F^B, through contact 7 of relay D^B in the normal position, back contact 8 of relay H^B, back point of contact 3 of relay S^B, contact 4 of each track relay T^B and T^A, front point of contact 3 of relay S^A, winding 11 of relay 85

90

- D^A , and contacts 5 of track relays T^A and T^B to the middle point of battery F^B . The energization of winding 11 of relay D^A will cause armature 7 of this relay to swing to the left 5 or reverse position, whereupon relay H^A will become energized by a circuit which passes from the lower terminal of battery F^A , through contact 7 and the winding of relay H^A to the middle point of the same battery. 10 Signal E^A will then be moved to the clear position by a circuit which passes from terminal B of a suitable source of current, through front contact 13 of track relay T^A , front contact 9 of relay H^A , and the operating mechanism of signal E^A to terminal 0 of 15 the same source of current.

It will be observed that the circuit for winding 11 of relay D^A cannot be closed unless contact 7 of relay D^B is in the normal position and back contact 8 of relay H^B is closed, thereby insuring that signal E^B is in the stop position. Furthermore, it will be observed that this circuit cannot be closed unless both track relays T^A and T^B are energized, that is, unless the entire block A—B is unoccupied.

When the train enters section A—C, it will deenergize track relay T^A , thereby opening the circuit for signal E^A at contact 13. Furthermore, the opening of contacts 4 and 5 of track relay T^A will open the circuit for the reverse winding 11 of relay D^A , but armature contact 7 of this relay will remain in the reverse position, so that relay H^A will remain energized. When the train passes out of section A—C and into section C—B, track relay T^A will become energized, but track relay T^B will become de-energized. The circuit for winding 11 of relay D^A will therefore remain open, but signal E^A will return to the proceed position, because its circuit will again become closed at contact 13 of track relay T^A . The foregoing statement is based on the assumption that relay S^A remains energized. If the operator has again de-energized relay S^A by the time the train passes point C, winding 10 of relay D^A will become energized to restore armature contact 7 of this relay to its normal position, thereby de-energizing relay H^A , so that signal E^A will not return to the proceed position when the train passes point C. In that event it will be necessary to wait until the train passes point B before signal E^A can again be cleared.

The operation of the apparatus in order to permit a train moving toward the left to enter block A—B will be obvious from the foregoing without detailed explanation.

Although I have herein shown and described only one form of apparatus embodying my invention, it is understood that various changes and modifications may be made 65 therein within the scope of the appended

claims without departing from the spirit and scope of my invention.

Having thus described my invention, what I claim is:

1. In combination, a block of railway track, track circuits including track relays for said block, a normally open remote controlled relay S for each end of said block, a directional relay D for each end of said block having a normal and a reverse winding and an armature which is moved to a normal or a reverse position according as the normal or reverse winding is energized and which remains in the position to which it was last moved when the relay becomes de-energized, a signal relay H for each end of said block, a circuit for the normal winding of each D relay including a back contact of the associated S relay, a circuit for the reverse winding of each relay D including a normal contact of the D relay for the other end of the block and a back contact of the H relay for the other end of the block and a back contact of the S relay for the other end of the block as well as a front contact of the associated S relay and front contacts of said track relays, a circuit for each H relay including a reverse contact of the associated D relay, and signals for said block controlled by said H relays. 95

2. In combination, a block of railway track, track circuits including track relays for said block, a normally open remote controlled relay S for each end of said block, a directional relay D for each end of said block having a normal and a reverse winding and an armature which is moved to a normal or a reverse position according as the normal or reverse winding is energized and which remains in the position to which it was last moved when the relay becomes de-energized, a circuit for the normal winding of each D relay including a back contact of the associated S relay, a circuit for the reverse winding of each D relay including a normal contact of the D relay for the other end of the block and a back contact of the S relay for the other end of the block as well as a front contact of the associated S relay and front contacts of said track relays, and signals for said block controlled by said D relays. 110

3. In combination, a block of railway track, track circuits including track relays for said block, a normally open remote controlled relay S for each end of said block, a directional relay D for each end of said block having a normal and a reverse winding and an armature which is moved to a normal or a reverse position according as the normal or reverse winding is energized and which remains in the position to which it was last moved when the relay becomes de-energized, a signal relay H for each end of said block, means for energizing the normal winding of each D relay when the associated S relay is 130

open, means for energizing the reverse winding of each D relay when the associated S relay is closed provided the armature of the D relay for the other end of the block is in normal position and the H relay for such other end of the block is open and the S relay at such other end of the block is open and also provided all of said track relays are energized, means for energizing each H relay when the armature of the associated D relay is in reverse position, and signals for said block controlled by said H relays.

In testimony whereof I affix my signature.
CHARLES A. BROOKS.
